DESIGN FOR A TABLE

Marshall C. Pumphrey, Los Angeles, Calif., assignor to Barker Bros. Incorporated, Los Angeles, Calif.

Application November 26, 1935, Serial No. 59,772

Term of patent 3½ years

To all whom it may concern:

Be it known that I, Marshall C. Pumphrey, a citizen of the United States, residing at Los Angeles, county of Los Angeles, State of California, have invented a new, original, and ornamental Design for a Table, of which the following is a specification, reference being had to the accompanying drawing, forming part thereof. The figure is a perspective view of a table, showing my new design.

The rear side is identical with the front side as shown in the drawing.

I claim:

The ornamental design for a table as shown and described.

MARSHALL C. PUMPHREY.
